UNITED STATES PATENT OFFICE.

WILLIAM HAMER, OF ELTON, BURY, ENGLAND.

STEAM GENERATOR.

Application filed May 19, 1919. Serial No. 298,055.

To all whom it may concern:

Be it known that I, WILLIAM HAMER, a subject of the King of Great Britain and Ireland, and a resident of Elton, Bury, in the county of Lancaster, England, have invented certain new and useful Improvements Connected with Steam Generators, of which the following is a specification.

This invention relates to steam generators of the Lancashire, Cornish and like types, having external side flues.

The brickwork which closes the front ends of the side flues of steam generators of the types referred to is carried up beyond the transverse or horizontal centre line of the boiler or boilers, and the inability of the brickwork to follow the expansion and contraction of the boiler or boilers frequently leads to disturbance thereof with leakage of cold air into the flues and loss of heat, and, in many cases, to bulging and eventual cracking of the brickwork. The object of the present invention is to provide a yielding joint between the shell of a boiler and the brickwork at the front end thereof which will readily give to and follow the expansion and contraction of the boiler and so prevent any disturbance of the brickwork, or leakage of cold air and loss of heat.

According to this invention, I provide at each side of the front end of the boiler one or more joint-members shaped to fit the shell of the boiler and pressed thereagainst by a spring or springs against and under the action of which they are free to yield to, and follow, the expansion and contraction of the boiler shell. Asbestos rope or other appropriate incombustible packing may be arranged between the joint-members and the boiler shell and the former may be arched, grooved or similarly formed to receive the packing.

In the accompanying drawing, Fig. 1 is a transverse section of a Lancashire boiler illustrating one embodiment of the invention, the section of the left hand half of Figure 1 being taken through the side flue and the section of the right hand half being taken through the front wall of the setting, and Fig. 2 is a part section to a larger scale on the line 2—2 in Fig. 1. Fig. 3 is a front elevation illustrating another embodiment

of the invention, and Fig. 4 is a part section to a larger scale on the line 4—4 in Fig. 3. Fig. 5 is an elevation partly in vertical section of a modified form of joint-member.

Referring first to Figs. 1, 2, 3 and 4 of the drawing, *a* is the boiler shell and *b* the brickwork setting of same. *c, c* are the internal flues of the boiler, *d, d* the external bottom flues into which at the rear end of the boiler the internal flues *c, c* lead, *e, e* the external side flues into which the bottom flues *d, d* open by passages *f, f* at the front end of the boiler and which lead to the chimney flue at the rear end of the boiler in the usual way, and *g, g* are the blocks upon which the boiler is supported.

Ordinarily, owing to disturbance of the brickwork of the front wall *b*¹ of the setting *b*, by the expansion and contraction of the shell, cold air leaks between the boiler shell and the front wall into the side flues *e, e* between the level of the supporting blocks *g, g* and the top of the side flues.

In order to prevent the aforesaid leakage of cold air into the side flues *e, e*, I provide at each side of the front end of the boiler shell *a*, a joint-member *h* having its face *h*¹ next to the shell, shaped to the external contour thereof, and of sufficient height to extend from below the bottom *e*¹ of the side flue *e* to above the top *e*² thereof. Preferably, the joint members *h* extend to the cover-flags *j* of the setting *b*. The joint-members *h* are formed with tail portions *h*² which are mounted to slide in one channel of double-channel guide-members *k* of I-section in plan. The joint members are pressed against the shell *a* by springs *m* which are arranged between the tail portions *h*² and the webs *k*¹ of the guide-members *k*. The springs *m* are positioned by being mounted on set screws *n* the stems of which pass freely through the holes *k*² in the webs *k*¹ and are screwed into the tail portions *h*². The faces *h*¹ of the joint-members *h* are preferably grooved or arched, as illustrated, or equivalently formed to receive asbestos rope or other appropriate incombustible packing *o* to make an air-tight joint between the joint-members *h* and the shell *a* and the brickwork behind the joint-members.

The joint-members *h* and the guide mem-

bers *k* may be built in the front wall *b*¹ of the setting *b*, as shown in Figs. 1 and 2. Or, as illustrated in Figs. 3 and 4, the guide-members *k* may be built in the front wall *b*¹ and the joint members may be arranged in recesses *b*² in the wall to afford free access to the packing *o* and for renewing same with the aid of a caulking tool.

The channels of the guide members *k* are packed with slag wool or other appropriate yielding packing *q* to prevent cold air from finding its way through the channels past the joint members and into the side flues.

The springs *m* while pressing the joint members *h* against the boiler shell allow the members to yield to and follow the movements of the shell under expansion and contraction. As the joint members always maintain air-tight joints between the boiler shell and the front wall of the setting, the front wall need not be in actual contact with the shell between the top and bottom of the side flues, thus avoiding any possibility of disturbance of the wall by the expansion and contraction of the shell.

If desired, and as illustrated in Fig. 5, the joint members *h* may be made in a plurality of sections *h*³.

Leakage of cold air into the upper part of the side flues between the top of the flues and the cover-flags *j*, may be prevented by the means described in my British Patent No. 105829.

What I claim as my invention, and desire to secure by Letters Patent is:—

1. In steam generators having external flues in a setting, means for maintaining an air-tight joint between the boiler shell and the front of the setting to prevent leakage of cold air therebetween into the side flues, comprising movable joint-members mounted between the front wall of the setting and the shell and means for pressing said joint-members against the shell so that they yield to and follow the movements thereof under expansion and contraction.

2. In steam generators having external flues in a setting, means for maintaining an air-tight joint between the boiler shell and the front of the setting to prevent leakage of cold air therebetween into the side flues, comprising movable joint-members mounted between the front wall of the setting and the shell, and a spring adapted to press said joint-members against the shell so that they yield to and follow the movements thereof under expansion and contraction.

3. In steam generators having external flues in a setting, means for maintaining an air-tight joint between the boiler shell and the front of the setting to prevent leakage of cold air therebetween into the side flues, comprising guide-members of channel section mounted in the front wall of the setting

at either side of the boiler, joint-members 65 slidably mounted in said guide-members, springs mounted between said guide and joint members and adapted to press the joint members against the boiler shell so that they yield to and follow the movements thereof 70 under expansion and contraction.

4. In steam generators having external flues in a setting, means for maintaining an air-tight joint between the boiler shell and the setting, comprising a movable joint-member bearing against the shell and adapted to yield to and follow the movements thereof under expansion and contraction, and incombustible packing arranged 75 between said joint-member and the shell. 80

5. In steam generators having external flues in a setting, means for maintaining an air-tight joint between the boiler shell and the setting, comprising a movable joint-member, means for pressing said joint-member against the shell so that it is free to yield to and follow the movements of the shell under expansion and contraction, and incombustible packing arranged between 85 said joint-member and the shell. 90

6. In steam generators having external flues in a setting, means for maintaining an air-tight joint between the boiler shell and the front of the setting to prevent leakage 95 of cold air therebetween into the side flues, comprising movable joint-members mounted between the front wall of the setting and the sides of the shell to bear against the latter and to yield to and follow the movements thereof under expansion and contraction, and incombustible packing arranged 100 between said joint-members and the shell. 100

7. In steam generators having external flues in a setting, means for maintaining an air-tight joint between the boiler shell and the front of the setting to prevent leakage of cold air therebetween into the side flues, comprising guide-members of channel section mounted in the front wall of the setting at either side of the boiler, joint-members 105 slidably mounted in said guide-members, springs mounted between said guide and joint members and adapted to press the joint-members against the boiler shell so that they yield to and follow the movements thereof under expansion and contraction, and incombustible packing arranged 115 between said joint-members and the shell. 115

8. In steam generators having external flues in a setting, means for maintaining an air-tight joint between the boiler shell and the setting, comprising a movable segmental joint-member, means for pressing said joint-member against the shell so that it yields to and follows the movements thereof under expansion and contraction, and incombustible packing arranged 120 between the shell and the joint-member. 125

9. In steam generators having external flues in a setting, means for maintaining an air-tight joint between the boiler shell and the setting, comprising movable segmental joint-members, means for pressing said joint-members against the shell so that they yield to and follow the movements thereof under expansion and contraction, incombustible packing arranged between said joint-members and the shell, and means for guiding said joint-members in their movements. 10

In witness whereof I have hereunto set my hand.

WILLIAM HAMER.
